UNITED STATES PATENT OFFICE.

ALBERT ABORN, OF DES MOINES, IOWA, ASSIGNOR OF ONE-THIRD TO FRANK L. MINER
AND ONE-THIRD TO ORIN G. CHESLEY, BOTH OF DES MOINES, IOWA.

CALENDAR.

1,321,498.

Specification of Letters Patent. Patented Nov. 11, 1919.

Application filed November 20, 1918. Serial No. 263,354.

To all whom it may concern:

Be it known that I, ALBERT ABORN, a citizen of the United States, residing at Des Moines, in the county of Polk and State of Iowa, have invented certain new and useful Improvements in Calendars; and I do hereby declare the following to be a full, clear, and exact description of the invention, such as will enable others skilled in the art to which

10 it appertains to make and use the same.

This invention refers generally to an indicating and recording device by means of which adjustable and exchangeable pieces of informative matter can be easily adjusted in the proper position and when so adjusted may be readily seen and read, and it is one of the objects of my invention to provide means of construction whereby devices of this kind may be cheaply and easily 20 manufactured from material obtainable at a low cost and from parts which can be easily shaped and assembled, and it is a further object of my invention to increase the adaptability of devices of this kind and at the same 25 time to reduce the number of parts necessary to make up a complete structure.

As here shown my invention is particularly applied to the construction of a calendar which when properly set may be used 30 for a very great number of years, but I wish it to be understood that my invention is not restricted thereto but may as well be applied for other indicating and recording purposes where informative matter is made up of different pieces of such matter contained upon 35 separate supporting surfaces. As applied to calendars my invention has for one of its objects to construct a kind of perpetual or long-time calendar, and it is a further object of the invention when applied to calendars to construct a calendar in which not 40 only the dates of the current, but also those of the succeeding week may be easily ascertained, and in which not only the particular 45 day may be easily read but in which the particular days of the week corresponding to each date may be easily determined. Other objects and advantages of my invention will appear from the following specification and from the drawings.

In the drawings which represent my invention as being embodied in a long-time calendar by way of example, Figure 1 is a longitudinal section of the preferred form 55 of construction of a calendar of this kind.

Fig. 2 is a top plan view of the device in the assembled condition. Fig. 3 is a detail view of the rotating instrumentalities. Figs. 4, 5 and 6 are plan views respectively representing the three chief disks of which the device is composed.

16 is a base plate of any suitable material having rotatably secured thereto a pivotal stud 15 rotatable on the pin 15' which is secured against rotation upon the stationary 60 base plate 16. The outer surface of the knob or pivotal stud 15 may be provided with informative matter, and in the present instance it has a series of fifteen radial sectors containing the names of the months in the 65 year arranged according to a certain system. At the bottom of the knob 15 a circular disk 2 is secured at the edge of which two rows 70 concentric with the knob 15 are arranged which are divided up in the present instance into twenty-eight radial sectors each and of which each row contains the names of the days of the week in consecutive order. The days in each sector are ten days distant 75 from each other. In the drawings the informative matter of the disk 1 is indicated at 10. Overlying the disk or wheel 1 another disk or wheel 2 is arranged so as to be rotatable around the knob 15. At the part surrounding said knob 15 the circular disk 2 80 is provided with a resilient upstanding flange 7 which embraces and engages with the said knob so as to partake in its rotation. The disk 2 may, however, also be held stationary by means hereinafter described so as 85 to allow of the disk 1 rotating independently of the said disk or wheel 2. This latter disk is preferably of larger diameter than the disk 1 and at the part corresponding to the concentric rows 10 of informative matter of 90 the disk 1, the disk 2 is provided with a concentric recessed part 6 connected by thin webs 6 or in any other suitable manner to the body part of the disk, 2. At the inner edge of said recessed part 6 the disk 2 is provided with a number of concentric rows 11 95 of informative matter, in the present instance with six rows containing 28 radial sectors each and representing the numbers of the days of the month in consecutive order 100 in each row. The days of the month corresponding to the same week day are arranged in radial succession, and immediately surrounding the recessed part 6 are rows of 105 dates ten days apart in radial succession, 110

and of which the dates of the inner row correspond to certain of the numbers nearer the center in each particular sector in accordance with a certain system. 5 The body part of the disk or wheel 2 covers the blank space of the underlying disk 1 and the two rows 10 of informative matter of said disk 1 are flanked on each side by the rows of numbers on the part 11 and 10 the ring 11' respectively of the disk 2 immediately adjoining the recessed part 6.

The flanged part 7 of the disk 2 immediately adjoining the knob 15 may consist for instance of spring acting teeth as clearly 15 shown in Fig 3 of the drawing.

Upon the disk 2 another disk 3 of smaller diameter and preferably of a width corresponding to the blank space of the underlying disk 2 is rotatably arranged in a similar 20 manner as the disk 2. At its inner edge surrounding the knob 15 and the flange 7 of the underlying disk 2 the said upper disk 3 is provided with a resilient flange, preferably consisting of a series of spring acting teeth 8 which are adapted to engage the teeth 7 of the underlying disk so as to be able to rotate disks 1, 2 and 3 by merely turning the knob 15. When the intermediate disk 2 is locked against rotation only, 30 the bottom disk 1 is rotated by operating the knob 15, inasmuch as the underlying disk 2 is held stationary the upper disk 3 which engages with the flanged part of said disk 2 will also be held stationary. This disk 3 in the present instance is all covered with informative matter 12, preferably in form of seven rows of 28 sectors each. Each concentric row contains the names of the week days in consecutive order. In radial succession 35 the week days of this part 12 are preferably ten days apart in accordance with the system on which this calendar has been calculated, but it is obvious that different arrangements of the week days in relation 40 to each other may be resorted to, and there may be other informative matter arranged upon the disk 3.

The entire structure is covered at the outside by a covering plate 4 which is provided 50 with a circular recess surrounding the knob 15 and the flanged parts 7 and 8 of the underlying disks and which are in engagement with the said knob 15. The covering plate 4 is provided with additional recessed parts 5 and 9 through which the informative matter 55 of all the underlying disks may be read with the help of the recess 6 of the disk 2. As here shown the recessed part 5 is preferably sector shaped and allows of reading 60 a corresponding sector of the disk 3 and of the body part of the disk 2 and the inner half of the corresponding sector of the bottom disk 1. Another recess preferably diametrically opposite the recess 5 is shown at 65 9 in the drawing as being of just sufficient

size to allow of viewing a figure of the outer ring 11' of the disk or wheel 2 and the next adjoining name of the week day in the outer row of the corresponding sector in the bottom disk 1, so that the indications in this 70 small window or recess 9 are taken from the outer row of the bottom disk and the date indications in the other recess 5 from the inner row of the bottom disk 1. Inasmuch as the arrangement of the several sectors on 75 the bottom disk 1 in the calendar system shown as an instance, is such that the diametrically opposite sectors on said disk 1 contain the same names of the days and in the same order relatively to the knob 15 it is 80 obvious that the diametrically opposite indications on the cover plate will refer to the current date and to a date ten days distant therefrom when employed in connection with the calendar system of the construction 85 shown in the drawing.

Other informative matter 13 surrounding the circular recess of the covering plate 4 refers to the setting of the calendar and to the numbers of the years and may be arranged so as to concentrically surround the 90 said recess, while other informative matter containing the names of the months may be arranged on that portion of the two sides of the sector shaped recess 5 which corresponds to the radial depth of the underlying small disk 3.

When applied to a time or date computing device or a calendar as hereinbefore described the device is set in accordance with 100 a certain key based on a certain system of date calculation by first adjusting the small disk 3 containing the names of the days of the week for a whole year, then turning the knob 15 with the disks 2 and 3 engaging 105 therewith until a certain number of the ring shaped part 11' of circularly slotted disk 2, the numbers 7, 14 or 21 for instance according to the computing system employed in the present instance, appears in the upper 110 window 9 of the covering disk 4. Then the covering disk 4 and the large circularly slotted disk 2 are locked together so as to keep the disk 2 from rotation and the knob or pivotal stud 15 is turned until the desired 115 month of the months' indications on its surface corresponds with one of a series of numbers arranged in a concentric circle between the circular hole at the center of the covering disk 4 and the surrounding series of 120 numbers of years. The computing device or calendar is then set. A key or a set of instructions accompany the computing device to facilitate the setting thereof and the finding of the particular dates.

It is obvious that my invention is capable of various modifications in accordance with the different systems of date computations employed, and as local conditions of use and of convenience of the operator may direct 125 130

and within the meaning of the claims hereunto appended, and it is also evident that my invention may be applied to a variety of other purposes, such for instance for the 5 purpose of compiling advertising or instructive or other informative matter from certain elements, and for similar objects.

It is also obvious that the informative matter on the various disks which latter may 10 be of any desired material, may be of any style desired, and letters as well as numerals and illustrative matter may be used.

Having described my invention what I claim is:—

- 15 1. In a device of the character described the combination with a base, of a rotatable disk mounted on said base, a pivotal stud secured to said bottom disk, additional superimposed adjustable disks of different and decreasing diameters rotatably mounted on said pivotal stud, an outer concentric ring around the edge of the base-secured rotatable disk, means to connect said ring to the lowermost additional disk at a concentric 20 distance thereof, resilient spring acting teeth at the inner edges of said additional disks and yieldingly engaging each other and yieldingly engaging said pivotal stud, informative matter on said ring, informative matter on the upper disk and informative matter on the underlying disks around the edges of the overlying disks, and a stationary covering plate engageable with said ring to keep said ring from rotation, oppositely disposed recessed parts on said covering plate, one of said recessed parts being of sectional shape 25 and disclosing part of the inner row of informative matter of the bottom disk and parts of the informative matter of the overlying disks, the other recessed part disclosing part of the informative matter of the 30 outer row of the bottom disk and part of the informative matter of said ring.
- 35 2. In a device of the character described in combination a base, a rotatable circular bottom disk mounted on said base, a circular

pivotal knob secured to said bottom disk, additional superimposed circular disks of different and decreasing diameters rotatably 40 mounted on said pivotal knob, an outer concentric ring around the edge of the bottom disk and means to connect said ring to the lowermost additional disk at a concentric distance therefrom, resilient spring acting 45 teeth at the inner edges of said additional disks and yieldingly engaging each other and yieldingly engaging said pivotal knob, informative matter on said ring, two concentric rows of informative matter near the 50 edge of the bottom disk and corresponding with the distance between the ring and the disk connected thereto, informative matter on the upper disk, and informative matter on the underlying disks around the edges of 55 the overlying disks, a stationary covering plate engageable with said ring to keep said ring from rotation, oppositely disposed recessed parts on said covering plate, one of said recessed parts being of sectional shape 60 and disclosing part of the inner row of informative matter of the bottom disk and parts of the informative matter of the overlying disks, the other recessed part disclosing part of the informative matter of the 65 outer row of the bottom disk and part of the informative matter of said ring.

In testimony whereof I affix my signature in presence of two witnesses.

ALBERT ABORN.
